UNITED STATES PATENT OFFICE.

PETER SAUP AND CHARLES HAUENSTEIN, OF CAIRO, ILLINOIS.

HARNESS-BUCKLE.

SPECIFICATION forming part of Letters Patent No. 624,688, dated May 9, 1899.

Application filed August 13, 1898. Serial No. 688,480. (No model.)

To all whom it may concern:

Be it known that we, PETER SAUP and CHARLES HAUENSTEIN, citizens of the United States, residing at Cairo, in the county of Alexander and State of Illinois, have invented 5 a new and useful Harness-Buckle, of which the following is a specification.

This invention relates to certain improvements in that class of harness-buckles used 10 to adjustably secure the trace to the tug and known as "trace-buckles," the object of the invention being to provide an improved buckle of this class in which the perforation of the trace is rendered unnecessary, the trace 15 and tug being firmly connected together and rendered readily adjustable upon each other without the necessity of cutting, punching, or otherwise marring or weakening either the trace or tug.

With this object in view our invention consists in the improved construction, arrangement, and combination of parts hereinafter 20 fully described, and afterward specifically pointed out in the claim.

In order to enable others skilled in the art 25 to which our invention most nearly appertains to make and use the same, we will now proceed to describe its construction and operation, having reference to the accompanying drawings, in which—

Figure 1 is a face view of a buckle constructed in accordance with our invention, illustrating also the tug and the end of the trace secured together thereby. Fig. 2 is an edge view of the same parts. Fig. 3 is a longitudinal sectional view taken on the plane indicated by the dotted line 3 3 of Fig. 1. Fig. 4 is a detail perspective view of the parts composing our improved buckle detached 35 from each other.

Like letters of reference indicate the same parts throughout all the figures of the drawings.

Referring to the drawings by letters, A indicates the main body or frame of the buckle, the sides of which are curved and the cross-bars A' A² of which are round and smooth. A wide cross-bar B, curved to conform with 40 the shape of the sides of the frame A, connects said sides and is perforated at B' at about its center to receive a rivet B², by which to connect a leather shield C to pre-

vent the buckle from galling the horse. The main body A is provided with the usual side loops D D' to receive the back and girth. 55

E indicates the trace-loop, which consists of curved sides E' and a flat cross-bar E², the loop being connected to the hame-tug F by means of a bolt or removable cross-bar F'.

G indicates a loop, which we shall herein-after designate the "crimping-loop," having curved sides G', a flat cross-bar G², and a round cross-bar G³.

H indicates the trace, which is provided with the usual loop H' for attaching to the 65 whiffletree.

The construction of our improved buckle will be readily understood from the foregoing description, and its operation may be described as follows: The tug and trace being 70 disconnected and it being desirous to connect them together adjustably, the end H² of the tug is passed through the crimping-loop G by passing it under the round cross-bar G³. The flat cross-bar G² having been passed through 75 the space I between the round cross-bar A² and the wide curved cross-bar B of the buckle-frame, the end H² is passed under the flat cross-bar G² of the crimping-loop. The flat cross-bar E² of the trace-loop E having been 80 passed upward through the space I' between the round cross-bar A' and curved cross-bar B of the buckle-frame A, the end H² of the tug is further passed under the flat cross-bar E² of the trace-loop E, and thence under the 85 flat leather loop J of the trace to confine the end. In this position, as clearly illustrated in the edge and sectional views, Figs. 2 and 3, a pull exerted upon the trace will cause the flat cross-bar E² of the tug-loop to bind 90 upon the outside of the trace and prevent its being moved with relation to the tug. A pull upon the trace by means of this connection will tend to straighten the crimped portion 95 H³, which will cause the trace to bind tightly between the cross-bars G² and G³ of the loop G and the cross-bar A² of the frame, a strain upon the cross-bar G³ causing the flat cross-bar G² to be tightly clamped against the outside of the trace.

From the foregoing it will be seen that we have provided a simple, cheap, and effective buckle for carrying out the expressed objects of our invention in which the trace and tug

are held together without the use of tongues and without the necessity of perforating either the trace or tug.

While we have illustrated and described the best means now known to us for carrying out our invention, we do not wish to be understood as restricting ourselves to the exact details of construction shown, but hold that any slight changes or variations therefrom, such as might suggest themselves to the ordinary mechanic, would be clearly comprehended within the limit and scope of our invention.

Having thus fully described our invention, what we claim as new, and desire to secure by Letters Patent of the United States, is—

A harness-buckle comprising a main body or frame having curved sides, round end cross-bars, and a wide central cross-bar, a loop adapted to be secured to the end of the tug having curved side bars and a cross-bar at each end, and a crimping-loop of substantially the same form as the tug-loop, the two loops being narrow enough to be passed through the spaces in the main body or frame between the wide central cross-bar and the end cross-bars, substantially as described.

PETER SAUP.

CHARLES HAUENSTEIN.
